INVENTOR
John Schulde.

BY

Harry A. Baime
ATTORNEY

UNITED STATES PATENT OFFICE.

JOHN SCHULDE, OF ST. LOUIS, MISSOURI.

REFRIGERATOR.

Application filed January 2, 1923. Serial No. 610,195.

To all whom it may concern:

Be it known that I, JOHN SCHULDE, a citizen of the United States, residing at St. Louis, State of Missouri, have invented certain new and useful Improvements in Refrigerators, of which the following is a specification.

My invention has relation to improvements in refrigerators of the display case type, and consists in the novel features of construction more fully set forth in the specification and pointed out in the claim. The invention relates more particularly to refrigerators wherein a mixture of ice and salt is availed of for obtaining the required temperature, said mixture being contained in a tank at one end of the display case, means being provided for the circulation of the resulting brine in the case.

20 The principal object is to provide a tank that is mounted on an axle within the case so that it may be tilted through the open door to facilitate loading. Another object is to provide vents near the top of the display section of the case to permit the warmer air to escape therefrom thus avoiding the accumulation of water or condensation on the glass panels.

Further objects will be better apparent 30 from a detailed description of the invention in connection with the accompanying drawings, in which—

Figure 1 is a front view of the display case with the front wall broken away at one end to disclose one of the refrigerator compartments; Fig. 2 is a composite vertical transverse section taken through the case on the line 2—2 of Fig. 1, and through the brine troughs on the line 2^a—2^a of said figure, the lower part of the ice tank being in elevation; Fig. 3 is a vertical longitudinal section of a refrigerator compartment taken on the line 3—3 of Fig. 2; Fig. 4 is a horizontal longitudinal section taken on the line 4—4 of Fig. 1.

Referring to the drawings, 1 represents a refrigerator display case having refrigerator compartments 2, 2 at the ends and a display compartment 3 therebetween, the latter compartment having a front wall composed of three glass panels 4, 4, 4, separated by mullions 5, 5. A vent 6 having branches 6', 6'' passes through each mullion near the top so that the warmer air rising within the compartment 3 may escape to the

outside, thus preventing the panels 4 from sweating.

A tank 7 for ice and salt, or other refrigerant, is mounted in each compartment 2 on an axle 8 passing through a hub 9 in said tank, the axle being supported in brackets 10, 10' mounted respectively on the end wall of the case and the bottom thereof. It will be observed that the hub 9 is considerably below and to the rear of the center of gravity of the tank so that the tank will fall toward the front of the case, when released from a near vertical position, against a spring bumper 11 mounted on the front wall. The object of thus mounting the tank 70 is to prevent its accidentally dropping through the door opening when the door is opened to replenish the ice supply in the tank, or for any other purpose. After opening said door the tank is manually rocked to 75 the dotted position (Fig. 2) when it is an easy matter to reload the refrigerant into the part of the open top projecting beyond the rear wall of the case. After each charge the tank may be bumped forward against 80 the bumper 11 to distribute and jolt down the ice to secure an even and compact supply.

A curved horn 12 of uniform width and tapered toward the top is mounted within 85 the tank, the large end of said horn passing through the inner side wall of the tank below the center thereof, and the small end (open at the top) being spaced a short distance from the outer side wall and secured 90 thereto by a channel 13 a short distance below the open top of the tank. The front and rear walls of the tank 7 taper slightly toward the bottom, and the bottom slopes downwardly toward the center thereof where 95 it is provided with an inwardly extending recess 14. The tank is provided with two discharge spouts 15, 15 for the salt brine, a spout on each side of the recess 14, said brine discharging from the spouts into the 100 troughs 16, 16 resting on the bottom of the case. In a double case (as shown in Fig. 1) there is a pair of troughs integrally formed, leading from each refrigerator compartment 2, the two pairs coming together at the center 105 of compartment 3 and having a common drain pipe 17.

A tube 18 passes through each trough 16, said tube being spaced from the sides of the trough and mounted in the end walls thereof. 110

The tubes are open at the ends and pass through the end walls of the trough thus forming a flue passage-way for air, through the brine in the trough. The brine is maintained at a constant level in the trough by the overflow discharge pipe 19 leading into the drain pipe 17.

The operation of my improved refrigerator is as follows:

- 10 Assuming the tank 7 to be filled with a freezing mixture, the compartment 2 will be cold. However, following natural laws, the air in the upper part of said compartment entering from the adjacent compartment 3 will not be as cold as the air in the lower part of compartment 2. After the air enters compartment 2 its temperature is reduced and it falls, some entering the horn 12, where it is further reduced in temperature by the surrounding refrigerant. Thus the air will move steadily downward through the horn 12 which enlarges toward the discharge opening to permit a free and unimpeded discharge of cold air into compartment 3. Cold

air will also be forced through the recess 14 25 and under the bottom of tank 7 into compartment 3 by the super-incumbent air that is being cooled by contact with the outer walls of tank 7. A further cooling effect is brought about in the compartment 3 by the 30 brine-filled troughs 6, 6, and flues 18 through which the air may pass and be cooled.

Having described my invention, I claim:

A refrigerator having a cooling compartment and a storage compartment, a refrigerant tank mounted in said cooling compartment, a horn disposed within said tank and spaced from the sides thereof, said horn having an inlet near the top of the tank for receiving the warm air from the top of the 40 storage compartment, and an outlet near the bottom of the tank leading into the storage compartment near the bottom thereof, said horn gradually increasing in cross-sectional area from the intake to the outlet thereof. 45

In testimony whereof I hereunto affix my signature.

JOHN SCHULDE.
